H. F. HURD.

FOLD COLLAR.

APPLICATION FILED NOV. 5, 1915.

Patented Feb. 15, 1916.

Inventor:
Hubbard F. Hurd,

By Frank C. Curtis
Attorney

UNITED STATES PATENT OFFICE.

HUBBARD F. HURD, OF TROY, NEW YORK, ASSIGNOR TO CLUETT, PEABODY & CO. INC.,
OF TROY, NEW YORK, A CORPORATION OF NEW YORK.

FOLD-COLLAR.

1,171,614.

Specification of Letters Patent. Patented Feb. 15, 1916.

Application filed November 5, 1915. Serial No. 59,771.

To all whom it may concern:

Be it known that I, HUBBARD F. HURD, a citizen of the United States, residing at Troy, county of Rensselaer, and State of New York, have invented certain new and useful Improvements in Fold-Collars, of which the following is a specification.

The invention relates to such improvements, and consists of the novel construction hereinafter described and subsequently claimed.

Reference may be had to the accompanying drawings, and the reference characters marked thereon which form a part of this specification. Similar characters refer to similar parts in the several figures therein.

The principal object of the invention is to save time and labor in providing a fold-collar with a series of necktie-retaining loops arranged in succession along the neighboring sides of its band and its folded-over top.

Other objects will appear in connection with the following description.

Figure 1 of the drawings is a front view in perspective of a fold-collar embodying my invention. Fig. 2 is a plan view of the same opened out flat.

Referring to the drawings wherein the invention is shown in preferred form, 1 is the band, and 2, is the folded-over top of a fold-collar, said top and band being attached to each other by a seam, 3, in the usual manner. In use, the top, 2, is folded over upon the band, as shown in Fig. 1.

In carrying out my invention, I provide near each end of the collar a necktie-retaining loop, 4, on the top and a similar necktie-retaining loop, 5, on the band, both being formed by a continuous strip, 4-5, of tape, which, when the collar is opened out flat, as shown in Fig. 2, extends diagonally from the lower edge of the band to a free edge of the top, crossing the seam 3. One edge of the tape is attached at 6, to the lower edge of the band preferably by inserting and securing the tape between the plies of the band, and the opposite end is attached at 7, to an end edge of the top, preferably by inserting and securing the tape between the plies of the top. The middle portion of the tape is attached at 8 to the body of the collar at substantially the line of junction of the band and top, either by the seam, 3, or by separate stitching, as desired. By extending a single tape thus, diagonally across both the band

and top, much time and labor can be saved in attaching the tapes to the body of the collar, and when the top is folded over upon the band, the loops, 4, and 5, will not be opposite one another, but will diverge downwardly from the fold-line of the collar, as shown in Fig. 1. I am thus able to obtain with a single piece of tape a successive arrangement of the two loops, 4 and 5, which permits the band of the necktie to be inserted through both loops, thus not only retaining and supporting the necktie, but serving also, when the necktie is knotted, to hold the ends of the top closely to the band to present a snug-fitting appearance at the front of the collar.

I prefer to have the two tapes near the respective ends of the collar extend, when the collar is opened out flat, divergently from the lower edge of the band to the respective end edges of the top, as shown in Fig. 2, so that the loops, 4, at their points of attachment, 7, are close to the corner portions of the folded-over top, whereby said corner portions are closely held and prevented from curling up when the loops are occupied by a knotted necktie.

What I claim as new and desire to secure by Letters Patent is—

1. A fold-collar having a band, a folded-over top, and a continuous tape extending diagonally across both the band and top when the collar is opened out flat, the opposite ends of said tape being attached respectively to the lower edge of the band and to an edge of the top, the intermediate portion of said tape being attached to the collar substantially at the junction of the band and top, whereby when the collar is folded, said tape forms downwardly divergent necktie-retaining loops between the band and the folded-over top.

2. A fold-collar having a band, a folded-over top, and two tapes extending, when the collar is opened out flat, divergently from the lower edge of the band severally to a free edge of the top, said tapes being attached at their middle and at their respective ends to the body of the collar.

3. A fold-collar having a band, a folded-over top, and a continuous tape extending, when the collar is opened out flat, divergently from the lower edge of the band to an end edge of the top, said tape being attached to the body of the collar at its ends

and at an intermediate point substantially at the junction of the band and top.

4. A fold-collar having a band, a folded-over top, and a continuous tape extending, 5 when the collar is opened out flat, diagonally across the line of junction of the top and band, said tape being attached at its ends respectively to the band and top, and being also attached at an intermediate point ap-

proximately at said line of junction of the 10 band and the top whereby, when the collar is folded, said tape forms downwardly divergent necktie-retaining loops between the band and the folded-over top.

In testimony whereof, I have hereunto set 15 my hand this 26th day of October, 1915.

HUBBARD F. HURD.
